UNITED STATES PATENT OFFICE.

PAUL BURKE, OF GREEN BAY, WISCONSIN, ASSIGNOR TO NORTHWEST ENGINEERING COMPANY, OF GREEN BAY, WISCONSIN, A CORPORATION OF WISCONSIN.

EXCAVATING SHOVEL

Application filed March 17, 1924. Serial No. 699,827.

To all whom it may concern:

Be it known that I, PAUL BURKE, a citizen of the United States of America, and resident of Green Bay, in the county of Brown 5 and State of Wisconsin, have invented new and useful Improvements in Excavating Shovels, of which the following is a description, reference being had to the accompanying drawings, which are a part of this specification.

The invention relates to excavating machines.

In excavating machines in which the dipper and its handle or stick are mounted to swing and shift relative to its supporting boom, it is sometimes necessary and highly desirable to hoist the dipper when the stick is in an extended position so that the contents of the dipper may be deposited at the 20 desired point. In machines of this general type a dipper stick of reasonable length, or one substantially longer than the distance between the shipper shaft and the point of the boom, can be thrust out when about in horizontal position, but hoisting from then on will gradually retract the dipper and stick until finally the sheave associated with the dipper meets the sheave at the outer end of the boom so that some means are necessary to hold the stick in extended position.

It has heretofore been quite common practice in some designs of shovels of this general type to use a brake controlled by the operator, either by hand or by foot, to prevent the retraction of the extended stick, but such constructions put an additional duty upon the operator and complicate the control mechanism. The object of this invention is to provide a brake which operates 40 automatically to prevent inward movement of the stick during hoisting and under a pre-determined tension so that slippage may occur under excessive loads imposed under some conditions of operation, and which 45 brake is automatically released when the stick is retracted without the use of additional controls.

A further and more particular object of the invention is to provide a shovel of the 50 rope-thrusting type in which the tension of the inward thrusting line is utilized to effect the release of a brake so arranged as to provide a predetermined braking force to restrain inward translation of the stick except 55 when such tension is applied, and to so asso-

ciate this brake with the operating cable that the free outward translation of the stick is not interfered with.

The invention further consists in the several features hereinafter set forth and more particularly defined by claims at the conclusion hereof.

In the drawings: Fig. 1 is a side elevation view of an excavating shovel embodying the invention; Fig. 2 is a detail sectional view 65 taken on the line 2—2 of Fig. 4; Fig. 3 is a detail sectional view taken on the line 3—3 of Fig. 1; Fig. 4 is a detail plan view of the shovel mechanism embodying the invention; Fig. 5 is a detail sectional view taken on the 70 line 5—5 of Fig. 3 with parts shown in full; Fig. 6 is a side elevation view of a shovel embodying the invention showing a modified cable arm arrangement; Fig. 7 is a detail plan view of shovel mechanism shown in 75 Fig. 6.

In the drawings the numeral 6 designates the boom, which may be of any suitable construction, vertically pivotally attached at its lower end to the rotating base 7 of the machine, which base is of well known construction.

A hoisting drum 8 and an auxiliary drum 9 are mounted on the base 7 in any suitable manner and driven from a prime mover, 85 not shown, on the base. The drums 8 and 9 may be of any well known construction equipped with clutches and brakes to control their operation. The boom is adapted to be raised or lowered and held in various positions of vertical adjustment by well known means, such as the cables 10 connecting pulleys 11 on the outer end of the boom to parts on the rotating base.

A shipper shaft 12 is secured in the arms 90 of a casting 13 on the boom and the saddle blocks or stick guides 14 are loose on this shaft. The dipper stick 15 is preferably of the divided type, that is, composed of two sections, each being slidably mounted in one of the blocks 14 and both adapted to swing with said blocks about the shaft 12. The dipper or shovel 16 may be of any suitable construction and is mounted, as usual, at the lower end of the stick.

A hoisting cable 17 passes from the drum 8 over a sheave 18 on a shaft 19 at the outer end of the boom, thence downwardly through a padlock sheave 20, pivotally connected to the dipper and preferably trans-

versely disposed with respect to the sheave 18, thence upwardly to the larger part of a compound drum 21 on which it is dead-ended, said drum being loosely mounted on the shaft 19. A cable 22 is dead-ended on the smaller side 23 of the compound drum 21 and passes once or more around a sheave or drum 24 on the shaft 12 and is dead-ended at the upper end of the stick in any suitable manner, as by anchorage to stop member 25, bolted at its ends to the sections of the stick. While a sheave may be used in place of the compound drum 21 with a continuous hoist and thrust cable passing over this sheave, the compound drum increases the leverage and thereby puts a greater pull on the crowding line 22 than on the line 17.

A cable 26, secured to and wound upon the drum 9, passes over a sheave 27 loose on the shaft 12, thence downwardly and around a sheave 28 at the lower end of the stick, thence upwardly and over a sheave 29 loose on the shaft 12 and is operatively anchored at this end to the boom, and in his particular instance to a brake-releasing member, hereinafter described, which acts against a fixed stop 30 on the casting 13 whereby when said cable 26 is operated to retract the stick the end 31 will be, for all practical purposes, anchored to the boom.

Associated with the drum 24 is a brake drum 32 loose on the shaft 12 and operatively connected to the drum 24 to move with it in one direction of rotation, that is counterclockwise, by means of a series of pawls 33, pivotally mounted on one face of the drum 24 and engageable with an internal ratchet wheel 34 formed in the drum 32. The brake drum 32 is adapted to be engaged by a brake-band 35. One end 36 of this band is secured to an arm 37 on a rock-shaft 38 mounted in the casting 13 and the other end of this band is secured to said casting as by an adjusting screw 39 which passes through an opening in a projection 40 of said casting and has an adjusting nut 41 thereon by which the tension of the brake-band may be adjusted. A release lever 42 is also connected to the shaft 38 and a spring 43 connecting said lever 42 with the boom exerts a tension upon said lever, tending at all times to rotate said lever 42 and arm 37 in a clockwise direction and hence set the brake. The end 31 of the cable 26 is secured to the lower end of the lever 42.

The operation of the construction just described is as follows: When the drum 9 is prevented from turning, by its brake, thereby holding the line 26, and the line 17 is pulled in, the dipper moves approximately in the arc of a circle of which the shipper shaft is the center. The dipper having been drawn in toward the machine and lowered upon the material to be excavated; and with the braking effect on the drum 9 released to

allow cable 26 to pay out, cable 17 is wound in, causing the dipper pivoted about the shaft 12 to swing relative to said shaft and shift outwardly with respect to the boom since the pull of said cable 17 turns the drum 21 putting a pull, here greater than the hoisting effect because of the compound drum, on line 22, which thereupon forces the dipper stick outward. Conversely, if it is desired to move the dipper stick farther in, hoisting with line 26 produces this effect. While the compound or differential drum is preferred, it is to be understood that the invention is not to be limited thereto. Thus, by a proper manipulation of the lines 17 and 26 any desired swinging and thrusting movement of the dipper and its handle may be effected. Furthermore, since the line 22 which effects the thrust is actuated by the hoist, a crowding effect equal to the full driving force of the engine is secured. With this and other constructions, however, when the stick is in an extended position and hoisting is continued until the stick is approaching, at, or above the horizontal, the hoisting cable 17 and other forces, such as the weight of the dipper and its contents, tend to shift the stick inwardly, which is not desired when the dumping of the dipper is to be effected with the stick extended.

With the brake, however, the drum 32 is prevented from rotating in a counterclockwise direction and, consequently, rotation of the drum 24 is prevented in the same direction, which is the direction of rotation induced by the tendency of the stick to move inward, and hence the brake will hold the stick against inward movement through the holding of the cable 22 associated with the stick, and the braking tension determined by the adjustment of the spring 43 is sufficient to hold the stick against inward movement under ordinary conditions. However, under some conditions of operation, as in the case where the stick is in a fully extended position and the stop member engages the saddle blocks 14, in order to relieve any tendency of the cable 22 being stretched or tensioned too greatly, the brake is allowed to slip, because under such conditions the brake tension is insufficient to prevent rotation of the drum. Thus, the brake may slip when a predetermined maximum tension has been set up in the cable 22 by its resisting the inward shifting movement of the stick and thus prevent injury to said cable. Under normal operation, however, the braking means prevents inward translation of the stick. If, then, with the stick 15 extended, the operator desires to move it inwardly, that is to retract it, the cable 26 is wound in, increased tension being applied until the end 31 of said cable swings the arm 42 toward and against the stop 30, thereby releasing the brake. Upon such release the dipper

stick 15 is free to move inwardly under the action of cable 26, said cable on being drawn in shortening up its run between the sheaves 27 and 29 and the sheave 28. It 5 will be understood that sufficient wraps of cable 22 are provided around the drum 24 so that that portion of said cable between said drum and the upper end of the stick cannot slip and, therefore, the sections of the 10 dipper stick will be held against inward movement, by the brake, as long as the cable 26 is allowed to remain slack. During the outward translation of the stick the drum 24 is free to turn in a clockwise direction as 15 the pawls 33 then ride freely over the ratchet wheel 34.

As illustrative of a construction in which the compound drum is not used, I show in Figs. 6 and 7 a shovel mechanism which 20 differs from that previously described only in the use of a single cable 17' for hoisting the dipper and moving it outwardly instead of the two cables 17 and 22, and as the other parts, including the brake mechanism and 25 its control, are the same the same numerals have been used. It will be noted in this case that the cable 17 is anchored to the drum 8, passes around the same, thence over the sheave 18 and around the padlock sheave 30 20 and up over a sheave 18' of the same diameter as the sheave 18 and loose on the shaft 19, and thence backwardly around the drum 24 and is dead-ended at the upper end of the stick by anchorage to the stop member 25. The operation of this construction 35 is similar to that previously described except that the pull on the hoisting portion of the cable 17' is the same as the pull on the crowding portion of said cable, it being noted that as the cable 17' is wound in by 40 its drum 8 the dipper handle is hoisted and at the same time the drum 24 is revolved in a clockwise direction thereby shortening up on the crowding run of said cable, that 45 is, the run between said drum and the upper end of the stick, and shifting the dipper stick outwardly.

From the foregoing description it will be noted that I have provided means which 50 provide a predetermined braking tension against inward translation of the stick when it is desired to hold the dipper stick extended, but which permits the dipper stick to be moved outwardly for the digging operations, and which tension is released without any special operation on the part of 55 the operator when it is desired to retract the stick, as such release occurs on the operation of the retraction mechanism for the 60 stick.

I desire it to be understood that this invention is not to be limited to any specific form or arrangement of parts except in so far as such limitations are included in the 65 claims or necessitated by the prior art.

What I claim as my invention is:

1. In an excavating machine, the combination with a boom, of a dipper and dipper handle mounted thereon to swing and shift with respect thereto, means for hoisting the 70 dipper, means for shifting the dipper handle inwardly, means including a brake for applying a predetermined and substantially constant force to counteract the shifting of the dipper handle in an inward direction, 75 and means controlled by said shifting means for releasing said brake.

2. In an excavating machine, the combination with a boom, of a dipper and dipper handle mounted thereon to swing and shift 80 with respect thereto, means for hoisting the dipper, means for shifting the dipper handle inwardly, means including a brake for applying a predetermined and substantially constant force to counteract the shifting of 85 the dipper handle in an inward direction, and means actuated by said shifting means for releasing said brake.

3. In an excavating machine, the combination with a boom, of a dipper and dipper 90 handle mounted thereon to swing and shift with respect thereto, means for hoisting the dipper, means for shifting the dipper handle inwardly, means including a brake for restraining the shifting of the dipper handle 95 in an inward direction under normal conditions but permitting slippage of said brake under excessive loads, and means actuated by said shifting means for releasing said 100 brake.

4. In an excavating machine, the combination with a boom, of a dipper and dipper handle mounted thereon to swing and shift with respect thereto, means for hoisting the dipper, means including a cable for shifting the dipper handle inwardly, means including a brake for applying a predetermined and substantially constant force to counteract the shifting of the dipper handle in an inward direction, and means, utilizing the 105 tension in said cable, for releasing said 110 brake.

5. In an excavating machine, the combination with the supporting boom, of a dipper and dipper handle mounted thereon to swing and shift with respect thereto, of means for hoisting and thrusting the dipper outwardly including a thrust-cable connected to said dipper handle, a brake to hold said dipper and dipper handle against 115 inward shifting movement within predetermined limits of tension set up in said thrust cable, a cable for retracting said dipper handle, and means under control of said re- 120 tracting cable and actuated thereby to release said brake.

6. In a power shovel, the combination of a boom, a dipper and dipper handle mounted thereon to shift and swing with respect thereto, a cable-drum, means including a 130

thrust-cable associated with said drum and dipper handle for shifting said handle outwardly, a brake-drum connected to turn with said cable-drum during inward movement of the stick and to be free of said drum during outward movement of the stick, a brake member associated with said brake-drum and to apply a constant braking force thereto whereby to hold said drums against turning and thereby hold said thrust-cable to prevent inward shifting movement of said dipper handle, means for shifting the dipper handle inwardly, and means actuated by said inward-shifting means to release said brake member.

7. In a power shovel, the combination of a boom, a dipper and dipper handle mounted thereon to shift and swing with respect thereto, a cable-drum, means including a thrust-cable associated with said drum and the dipper handle for shifting said handle outwardly, a brake for said drum permitting free outward movement of said sticks but operating within predetermined tension limits for said thrust-cable to hold said drum and cable to prevent inward movement of said handle, a retracting cable for shifting the dipper handle inwardly, and means, actuated by said retracting cable, to release said brake.

8. In a power shovel, the combination of a boom, a dipper and dipper handle mounted thereon to shift and swing with respect thereto, a cable-drum, means including a thrust-cable associated with said drum and

dipper handle for shifting said handle outwardly, a brake-drum having a pawl and ratchet connection with said cable-drum to turn with said drum during inward movement of the stick and be free of said drum during outward movement of said stick, a brake member, associated with said brake-drum to apply a constant braking force thereto whereby to hold said drums against turning and thereby hold said thrust-cable to prevent inward shifting movement of said dipper handle, means for shifting the dipper handle inwardly, and means actuated by said inward-shifting means to release said brake member.

9. In a power shovel, the combination of a boom, of a dipper and dipper handle mounted thereon to shift and swing with respect thereto, a shipper shaft having a cable-drum mounted thereon, a thrust-cable passing over said drum and connected to the upper end portion of the dipper handle, a brake-drum having a one-way driving connection with said cable-drum, brake means acting on said brake-drum to restrain its movement in the direction of drive to hold said cable-drum and thereby prevent inward shifting movement of said dipper handle, a retracting cable for shifting said dipper handle inwardly, and means, actuated by said retracting cable, for releasing said brake means.

In testimony whereof I affix my signature.

PAUL BURKE.
